ASH TRAY

Duey S. Leong, New York, N. Y.

Application April 22, 1949, Serial No. 2,197

Term of patent 14 years

(Cl. D85—2)

To all whom it may concern:

Be it known, that I, Duey S. Leong, a citizen of the United States, residing at New York, in the county of New York and State of New York, have invented a new, original, and ornamental Design for an Ash Tray, of which the following is a specification, reference being had to the accompanying drawings, forming a part thereof.

The dominant features of my design reside in those portions shown in full lines.

I claim:

The ornamental design for an ash tray, as shown and described.

DUEY S. LEONG.
